Primary Examiner — Philip S Hyder(74) *Attorney, Agent, or Firm* — Tucker Ellis LLP(57) **CLAIM**

The ornamental design for a release pull of ratchet, as shown and described.

DESCRIPTION

FIG. 1 is a perspective view of a release pull of a ratchet showing my new design;

FIG. 2 is another perspective view thereof;

FIG. 3 is a front view thereof, shown in reduced scale relative to the perspective views;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken line showing of the ratchet structure is provided for purposes of environment and forms no part of the claimed design.
